GIRDLE

Carl R. Glines, Dover, Del., assignor to International Latex Corporation, Dover, Del., a corporation of Delaware

Filed Oct. 23, 1962, Ser. No. 72,220

Term of patent 14 years

(Cl. D20—2)

FIG. 1.

The dominant feature of the design resides in a keystone-shaped front panel having a cluster of V-shaped decorative stitchings in the upper portion of it and a rear panel having edges that are pronouncedly divergent from top to bottom.

I claim:

The ornamental design for a girdle, as shown and described.
